Primary Examiner—Joel Sincavage*Attorney, Agent, or Firm*—Jerry M. Presson; David L. Tarnoff**[57] CLAIM**

The ornamental design for a dead front electrical connector for recharging electric vehicles, as shown and described.

DESCRIPTION

FIG. 1 is a rear perspective view of a dead front electrical connector for recharging electric vehicles showing my new design;

FIG. 2 is a right side elevational view of the dead front electrical connector for recharging electric vehicles shown in FIG. 1;

FIG. 3 is a bottom plan view of the dead front electrical connector for recharging electric vehicles shown in FIGS. 1-2;

FIG. 4 is a top plan view of the dead front electrical connector for recharging electric vehicles shown in FIGS. 2-3;

FIG. 5 is a front elevational view of the dead front electrical connector for recharging electric vehicles shown in FIGS. 1-4; and,

FIG. 6 is a rear elevational view of the dead front electrical connector for recharging electric vehicles shown in FIGS. 1-5.

The broken line showing in FIGS. 2, 3 and 6 is included for the purpose of illustrating environmental structure only and forms no part of the claimed design.
